APPARATUS FOR SEPARATING LIQUIDS AND SOLIDS

Filed Sept. 10, 1927

INVENTOR
Hans C. Behr.
BY *Chas. Lynde Russell*,
his ATTORNEY

UNITED STATES PATENT OFFICE.

HANS C. BEHR, OF SCARSDALE, NEW YORK.

APPARATUS FOR SEPARATING LIQUIDS AND SOLIDS.

Application filed September 10, 1927. Serial No. 218,719.

This invention relates to and has for an object to provide centrifugal apparatus for continuously separating liquids and solids from a mixture, one application being the freeing of fine coal from water.

The apparatus herein illustrated is useful in carrying out the method set forth in my copending application Serial No. 216,810 filed the 1st day of September, 1927 for improvements in continuous separation of liquids and solids.

In the drawings accompanying this specification, one practicable embodiment of my invention is illustrated, in which drawings,

15 Figure 1 is a central vertical section of the apparatus, and

Fig. 2 is a cross section taken on a plane at about the line 2—2 of Figure 1, the outer housing being omitted.

20 In the present illustration, the movable parts rotate about a vertical axis which is represented as the common axis of the shaft, 5, and the sleeve or hollow shaft, 6, which surrounds it.

25 The material is preferably fed into the machine through a centrally disposed hopper, 7, having a throat or discharge tube, 8, extending into the rotary elements, presently to be described.

30 For the purpose of simplifying this description, the mechanism in the form illustrated will be described in detail, although it will be obvious various changes in detail of construction may be made.

35 The material fed through the hopper, 7, and mouth, 8, passes outwardly by centrifugal force through four radially disposed passages, 9, each of which embodies a vertically disposed screen, 10, the screen being located

40 a little to one side of the true radial line, and in the present illustration are substantially tangential to the inner wall of the mouth, 8. The screen surface is constructed and adapted after the manner of the impeller blades of

45 a centrifugal pump. The inner rotary body in which the passages, 9, are formed and which carry the screens, is illustrated in the form of a casting formed with a series of screen supporting portions, 11, each of which

50 has across its face a plurality of channels, 12,

permitting the outlet of the liquid, and a plurality of ridges, 13, for supporting the screen. The ends of the screen, 14, are shown bedded in grooves in the portion, 11, although other means may be employed if desired for holding them in position. The outlet for the liquid which is passed through the screen is shown as a vertical hole or duct, 14, leading to a spout, 15, and fed by means of a series of openings, 16, extending from the space back 55 of the screen to the duct, 14.

The liquid from the spout, 15, flows into an annular pan, 17, and from this by means of a discharge opening, 18, into another annular pan, 19, from which it is led off to some 60 suitable receptacle by a pipe, 20.

The member carrying the radial discharge openings, 9, and the screens, 10, is shown 65 standing from a bottom plate, 21, which is shown supported by the flanged head, 22, of the shaft, 5, and, in the present illustration, secured thereto by means of a nut, 23.

A series of ridges, 24, are shown disposed in the openings, 9, for the purpose of obstructing a too rapid outward flow of the mixture being treated, and at the same time for preventing excessive pressure on the screen, 10. The material passing over these ridges has a tendency to deposit a certain quantity of the solid matter between the ridges and to 70 form a surface indicated by the dotted lines, 25, which will represent the angle of repose of the material incident to its character and rapidity of movement. For the purpose of preventing the formation of vacuums behind 75 these ridges, openings, 26, are provided. If a solid walled passage were provided having the restricted area afforded by the ridges and the banked up material, a great amount of pressure would be exerted on the screen, much 80 greater than that which is afforded by the varying and automatically regulated restriction caused by the device herein illustrated.

In the mechanism described and illustrated in my copending application above identified, 85 the centrifugal component only of the forces due to rotation is utilized for the separation of the materials. According to this present invention, however, only the tangential component of the forces due to rotation is made 90 100

use of for the separating process, the liquid by its inertia leaving the solids and passing through the screen, 10, while said solids are being accelerated centrifugally as they move 5 outwardly by the centrifugal forces.

In my above noted earlier filed application, I explained a certain principle of centrifugal separation, namely, that if the material under treatment is retarded in its otherwise 10 rapid centrifugal movement across the screen, particularly at the earlier stages of such movement, the solid material will not pack and the liquid will be thrown off from it and carry less of the finer portions of the solid 15 material than when the movement is rapid or when it is effected by means of scrapers. That principle is utilized in this present apparatus. At the very beginning of the outward travel 20 of the material the liquid is permitted to readily flow from it and does flow in practically the pure condition, unaccompanied with even the finer portions of the solid material. The solid material as it approaches the outer portion of the screen is practically freed 25 from liquid.

In the illustrated mechanism there is shown a top plate, 27, which is bolted to the plate, 21, and is consequently fast with the screens 10 and the shaft 5 downwardly. Rim or flange, 28, is shown projecting downwardly from the plate 27, and having an outwardly extending flange, 29. The inside of the rim, 28, is located at some little distance from the ends of the screens, 10. In operation, after the mixture 35 has filled all the spaces between the obstructions or ridges, 24, up to its angle of repose, 25, the material then passes over the screen, 10, in the separating capacity and the solid material banks up against the inside of 40 the rim, 28, from which it is removed by a series of blades, 30, these blades being located in a circle and traveling between the outer ends of the screens and the inner surface or wall of the rib, 28. The blades are caused to 45 move at a speed differing from the rotary speed of such wall. In the present instance, the blades travel at a faster rate of speed than the rate of travel of the wall and the parts carrying the screens, 10, such blades being 50 fast on an inturned rim, 31, formed on the plate, 32, which in turn is bolted to the flanged head, 33, of the sleeve shaft, 6.

The shaft, 5, which is shown suitably mounted in the machine frame, as is also the 55 shaft, 6, is driven by means of a pulley, 34, and a belt, 35, from some suitable source of power. The shaft, 5, is shown carrying a gear wheel, 36, in mesh with a gear wheel, 37, fast on a shaft, 38. The shaft also carries a gear 60 wheel, 39, meshing with a gear wheel, 40, carried by the sleeve shaft, 6. The number of teeth on the several gear wheels is so proportioned that the shaft, 5, drives the shaft, 6, forward at a rate of speed slightly in excess 65 of the rotation of the shaft, 5, so that the

blades, 30, travel somewhat faster than do the screens, 10.

The rim, 28, is provided with a number of openings, 41, through which the solid material received from the screens, 10, on the inside of the rim and advanced about it by blades, 30, will be discharged. The discharge is into the space, 42, and against the inner slanting face, 43, of the outer cover, 44. These discharge openings are preferably located out of the direct path of travel of the material in leaving the passages 9.

By having many blades, 30, the movement of the solids may be practically continuous. A few blades could be so arranged that the 80 material would be caused to have an intermittent movement over the screens, 10.

The intensity of the separating effect is controlled by the position of the screens, 10. Should these be curved forwardly to impede 85 the travel of the solid material, of course it is apparent that a more intense separating effect will be secured.

From the foregoing, it will be apparent 90 that this apparatus provides for a process of continuously separating liquid from a mixture with solids, in which the mixture, while being retarded by means rotating continuously at a uniform rate, is subjected to a gradual increasing separating force, as the mixture is 95 propelled outwardly over the foraminous surface by a centrifugal force while being tangentially accelerated, and in which such outward progress of the mixture and the discharge of the dried material are controlled by 100 means acting beyond the limits of the screen surface, which controlling means rotate the material at a different rate from the rate of rotation of the mixture under treatment.

Having described my invention I claim 105 and desire to secure by Letters Patent:

1. In a centrifugal apparatus the combination with a screen constructed and adapted to act after the manner of the impeller blades of a centrifugal pump whereby the forces due to rotation act to expel the liquid through the screen surface and cause it to pass through the screen against the direction of rotation thereof and means for rotating the screen, of means for supplying a stream of material to the screen, a wall disposed outwardly of the discharge end of the screen for receiving the material therefrom, and a series of movable blades for removing the material from the said wall. 110 115

2. In a centrifugal apparatus the combination with a screen disposed in a substantially vertical position and means for rotating this, of means for supplying a stream of material to the screen, a wall disposed outwardly of the discharge end of the screen for receiving the material therefrom, a series of movable blades for removing the material from the said wall, and means for causing 120 125 130

said blades to move at a speed differing from the rotary speed of the said wall.

3. In a centrifugal apparatus the combination with a rotary body, of a plurality of vertically disposed screens carried by such body, the rotary body having a circularly disposed wall beyond the discharging ends of the screens, a circular series of blades for engaging the wall and removing the material carried thereby, and means for rotating such blades at a speed different from the speed of rotation of the screens and material receiving wall.

4. The combination with a rotary body having centrally disposed means for receiving material to be treated, of a plurality of screens disposed in a substantially vertical position, each arranged tangentially to a small circle concentric with the axis of rotation, the screen supporting portion of the body being provided with channels extending in substantially the same radial direction for receiving the liquid, the tangential component of the forces due to rotation being made use of for the separating process, the liquid by its inertia leaving the solids and passing through the screen while said solids are being accelerated centrifugally as they move outward by the centrifugal forces, and

20 a circular wall carried by said rotary body and located beyond the discharge ends of the screens for receiving the solid material and impeding the flow of the solid material outwardly over the screen, and a circular series

25 of blades rotating between the discharge ends of the screens and such circular wall for removing at a predetermined rate the banked up material, the circular wall being provided with a plurality of ports through

30 which the material carried by the blades is discharged.

5. The combination with a rotary body and a centrally disposed pipe for supplying material to be treated, of a plurality of screens each arranged tangentially to the circular bore of the supply pipe, the portion of the body for supporting each screen being provided with channels extending in substantially the same direction as the screen

45 for receiving the liquid, a wall disposed outwardly of the discharge end of the screen for receiving the material therefrom, a series of blades for removing the material from said wall, and means for causing said blades to

50 move at a speed differing from the rotary speed of said wall.

6. The combination with a rotary body and a centrally disposed pipe for supplying material to be treated, of a plurality of screens each arranged tangentially to the circular bore of the supply pipe, the portion of the body for supporting each screen being provided with channels extending in substantially the same direction for receiving

60 the liquid, a circular wall disposed out-

wardly of the discharge ends of the screen and adapted to rotate therewith for receiving the material from the screens, there being discharge openings in the wall located out of the direct path of travel of the material leaving the screens, a series of blades for removing the material from the wall, and means for causing such blades to move at a speed differing from the rotary speed of the wall.

Signed at New York, N. Y. this seventh day of September, 1927.
